United States Patent Office

Des. 210,379
Patented Mar. 5, 1968

210,379

FRENCH CRADLE TELEPHONE

George D. Perkins, Pasadena, Calif., assignor to American Telecommunication Corporation, Los Angeles, Calif., a corporation of California

Filed July 20, 1967, Ser. No. 7,904

Term of patent 14 years

(Cl. D26—14)

FIG. 1 is an elevational view showing the front of the new design;

FIG. 2 is a top plan view showing the top of the new design;

FIG. 3 is an elevational view showing the rear of the new design; and

FIG. 4 is a right side elevation thereof, the left side of the telephone base is substantially the same in appearance except for the addition of the cord element.

I claim:

The ornamental design for a French cradle telephone, as shown and described.
